CLAIM

The ornamental design of a paint applicator device, as shown and described.

DESCRIPTION

FIG. 1 is a front perspective view of a paint applicator device; FIG. 2 is a left side elevation view, the right side being a mirror image;

FIG. 3 is a front elevation view of FIG. 1;

FIG. 4 is a rear elevation view of a FIG. 1;

FIG. 5 is a top plan view of FIG. 1; and,

FIG. 6 is a bottom plan view of FIG. 1.

The structure shown in broken lines illustrates portions of the device that form no part of the claimed design.
